UNITED STATES PATENT OFFICE.

PAUL MAUSOLFF, OF FRANKFORT-ON-THE-MAIN, GERMANY, ASSIGNOR TO ROESSLER AND HASLACHER CHEMICAL CO., OF NEW YORK, N. Y., A CORPORATION OF NEW YORK.

SUBSTITUTE FOR SOAP FOR WASHING, CLEANING, AND BLEACHING PURPOSES.

941,158.

Specification of Letters Patent. Patented Nov. 23, 1908.

No Drawing.

Application filed January 18, 1908. Serial No. 411,528.

To all whom it may concern:

Be it known that I, PAUL MAUSOLFF, a citizen of the United States of America, residing at Frankfort-on-the-Main, Germany, have invented certain new and useful Improvements in Substitutes for Soap for Washing, Cleaning, and Bleaching Purposes, of which the following is a specification.

10 This invention relates to a new and useful composition of matter adapted for washing and cleaning purposes and has as its object a harmless mixture which will give off active oxygen when dissolved in water, while at the 15 same time it will not prove harmful to the fiber or color of textiles or other organic substances.

There have been known and recommended for washing purposes substances which give 20 off active oxygen when in use, like sodium peroxid, permanganate of potash or liquid hydrogen peroxid. However, it is a well known fact that liquid hydrogen peroxid requires breakable glass packages and also involves a very high cost of transportation 25 through the large quantity of useless liquid carried along with its oxygen. It is likely to be quickly damaged or altogether spoiled by unfavorable weather and climatic influences, and it is difficult or altogether impossible 30 to bring it before the consumer economically in the necessary small quantities. The use of hydrogen peroxid for such purposes has, therefore, been insignificant. As another 35 oxidizing substance sodium peroxid has been proposed for this use, but it is not a product that can be safely given into the hands of the general public on account of its liability to inflame organic substances. Furthermore, when dissolved in water it forms 40 caustic soda and makes such a strong alkaline bath, that it is sure to have some serious effect upon the fiber of the material with which it is used or upon the hands of the 45 person using it. It also has too strong an influence upon the color of textiles, etc., owing to its extreme alkalinity. To overcome these difficulties it has been proposed to use sodium peroxid in direct mixture with certain 50 substances forming a non-objectionable and soluble salt with the caustic soda which results when sodium peroxid is dissolved in water. This has proven impracticable because the salts mixed with the sodium peroxid

contain water which brings about a decomposition of the sodium peroxid. To obviate this latter drawback it has been proposed to supply sodium peroxid in combination with such salts, in receptacles having different compartments so that the sodium peroxid remains separated from the other elements and only decomposes as the mixture is put into water, at which time the caustic soda is bound with the acid of the salts. But this expedient requires the most careful packing and even then the safe use of sodium peroxid cannot be guaranteed for the general public. Permanganate of potash like sodium peroxid is liable to inflame organic substances and for other well-known reasons would not be suitable for the object in view.

This invention relates to the use of a distinct class of harmless peroxidized compounds which are neither extremely caustic or liable to inflame organic substances, nor inconvenient to pack and forward, or quickly decomposed like hydrogen peroxid, such as sodium perborate, ammonium perborate, sodium percarbonate, potassium percarbonate, sodium-persulfate, potassium persulfate or ammonium persulfate, in combination with other substances which do not oppose but assist or supplement the washing and cleaning effect.

It has been attempted to mix a peroxidized compound with soap, and it has been asserted that it is necessary to do so, in order to preserve sufficiently the oxygen until use by incorporating the peroxidized compound in the soap body. It has, however, been discovered, that this is not necessary and that these peroxidized compounds as hereinbefore described are quite well preserved without the assistance of soap. On the other hand soap, on account of its fatty and adhesive properties, is not so conveniently and easily mixed with peroxidized compounds like other substances such as borax, or sal ammoniac or soda, etc., which have a cleaning effect of their own. The peroxidized compounds furnish an entire substitute for soap in washing and cleaning, and by adding to them substances like the before named which readily mix with the peroxidized compounds, the further advantage is obtained, that the admixture of soda, etc., acts on all impurities which can be removed mechanically, while the oxygen removes those

impurities which are not affected or removed by the other cleaning substance. The latter also may be a much less expensive material than soap and assist in further reducing the 5 cost of the peroxidized compound to the consumer, while having additional action as before stated.

The peroxidized compounds with the admixtures as described will not prove harmful 10 to the fiber or color of the textiles or other organic substances, nor present any danger whatever.

As an example of the practicable use of the invention it has been found satisfactory 15 to combine 80 to 90 parts of sodium perborate with 20 to 10 parts by weight of borax. Of this mixture 3 ounces by weight have been found to give satisfaction when used with 3 gallons of water. It is obvious that 20 other proportions can be employed according to special conditions or as to the object to be attained.

The composition of matter as described is dissolved in cold or warm water, or, if the 25 action of the oxygen is desired to be accelerated, the water will be gradually heated to boiling point. In either case a homogeneous solution of the component parts is quickly effected. It is obvious that instead 30 of one substance like soda there can be used 2 or more different powders of like properties as an admixture, for instance 5 to 10% borax and 5 to 10% soda or other proportions as desired. In the same manner several 35 peroxidized compounds, with borax or soda in suitable proportions, can be mixed.

There are other peroxidized compounds than those herebefore mentioned such as 40 peracid salts of the alkaline earth metals like perborate of magnesium, or peroxids of the alkaline earth metals like calcium peroxid or magnesium peroxid, or the peracid salt of a heavy metal like zinc perborate, etc., which require the addition of an (preferably 45 solid) acid like oxalic, or citric, or an acid salt like bi-sulfate of soda, in the necessary proportion, to liberate their oxygen more freely in plain water.

By the use of the term "peroxidized com-

pounds" it is not intended to limit the scope 50 of this invention to any particular peroxidized compounds. The term "harmless" is intended to distinguish those compounds, which will not cause spontaneous combustion with organic matter from those which will 55 cause such.

It is obvious that other elements may be added to the mixture as a filling or to accomplish other results not inconsistent with the use of such mixture without departing 60 from the spirit of the invention. It is also clear that without departing from the spirit of this invention the composition of matter, instead of in a powder form, can advantageously be used also in compressed tablet 65 form, whenever it is desired.

What is claimed and desired to be secured by Letters Patent is:—

1. A substitute for soap for washing, cleaning and bleaching purposes consisting 70 of a mixture of a harmless peroxidized compound and soluble inorganic alkaline material.

2. A substitute for soap for washing, cleaning and bleaching purposes consisting 75 of a mixture of a harmless peroxidized compound and alkaline material comprising borax.

3. A substitute for soap for washing, cleaning and bleaching purposes consisting 80 of a mixture of a harmless peroxidized compound, soda and borax.

4. A substitute for soap for washing, cleaning and bleaching purposes consisting 85 of a mixture of sodium perborate and alkaline material comprising borax.

5. A substitute for soap for washing, cleaning and bleaching purposes consisting of a mixture of sodium perborate, soda and borax. 90

In testimony whereof I have signed my name to this specification in the presence of two subscribing witnesses.

PAUL MAUSOLFF.
